UNITED STATES PATENT OFFICE.

ELMER A. SPERRY, OF BROOKLYN, NEW YORK.

MEANS FOR DETECTING SUBMARINE BOATS.

1,427,560.

Specification of Letters Patent. Patented Aug. 29, 1922.

Application filed June 7, 1917. Serial No. 173,276.

To all whom it may concern:

Be it known that I, ELMER A. SPERRY, a citizen of the United States of America, residing at 1505 Albemarle Road, Brooklyn, 5 in the county of Kings and State of New York, have invented certain new and useful Improvements in Means for Detecting Submarine Boats, of which the following is a specification.

- 10 This invention relates to a means for communicating the presence and location of submarine vessels. It has been proposed to employ for this purpose, a snare net or nets located under the water and adapted to be 15 engaged by the submarine, a signalling means being employed, such as a buoy containing radio transmission apparatus, to transmit signals to a patrol boat indicating that the net has been struck or carried away.
- 20 The main object of this invention is to improve upon apparatus of this character whereby it is rendered suitable for use upon the high sea.

Referring to the drawings in which what 25 I now consider the preferred forms of my invention are shown:

Fig. 1 is a view of a net snare showing two adjacent net units thereof, and the signalling apparatus in the inoperative position.

Fig. 2 is an enlarged sectional view of the bottom portion of the signalling buoy showing the signal operating and anchoring means.

35 Fig. 3 is an enlarged view of the snap hook used thereon.

Fig. 4 is an enlarged view of one of the reels used on the bottom of the net for taking up the slack in the connecting cables.

40 Fig. 5 is an elevation partly in section of the complete signalling buoy.

Fig. 6 is a sectional view of a modified form of signal operating mechanism.

45 Fig. 7 is an enlarged view of the separable connections employed between the nets.

Figs. 8 and 9 are two views of means employed to fasten the nets securely together when they are being launched or laid.

50 Fig. 10 is a detail sectional view showing the attachment of the mast to the float.

Preferably the net snare or barrier I propose to use comprises a plurality of nets, two of which are illustrated at 1 and 2 in Fig. 1. The said nets are preferably formed 55 of galvanized steel wire or cable with a large mesh and are supported at the top by a

plurality of buoys 3. In order to hold the nets in place, each net is secured to the adjacent net and also to an anchoring means such as an anchor cable 4, which may extend 60 throughout the length of a number of nets. Both connections are preferably separable, however, so that any net which is engaged may be readily detached. The said cable is shown as supported from the nets by 65 wires 5 having a shearing pin 6 or equivalent form of separable connection located therein. When used in deep water the cable is preferably provided with a plurality of buoyant members 7 adapted to support the 70 greater portion of the weight of the cable, but to leave it somewhat heavier than water. Each of the nets is shown as provided with a reel 8 or 8' on which is wound rope or wire 9 or 9' extending to buoy 10. Reels 8 and 8' 75 are preferably provided with a brake or spring 20 adapted to prevent its unwinding unless the rope 9 is pulled with substantial force. Said buoy is made very buoyant and is shown as provided with a weight 11, normally secured thereto and adapted to overcome the greater portion of its buoyancy so that the anchoring effect of cable 4 will not be overcome, or materially changed if the buoy should be released from it. The buoy 80 is also anchored to the cable 4 by means of a wire 12. All of the connections 9, 9' and 12 and the weight 11 are shown as secured to the buoy by a common means such as snap hook 13 which is normally held closed by 85 loop 14. The tongue 15 of said hook is pivoted at 16 to the body or base 17. Said base is shown in Fig. 3 as constructed of two bars, their upper ends being overlapped at 18 to form eye 19, while the lower ends are 90 forked to receive the tongues 13.

In addition to the rope or wire 12, the buoy is preferably also secured to the anchor cable by means of a second rope 21. Rope 21 however is much longer than rope 12, 100 being designed to allow the buoy to rise to the surface but to prevent its drifting away from the cable. Preferably the slack of said rope is taken up by winding it on a reel 22 located in the base portion 60 of the 105 buoy. Preferably the outside layer of cable 21 proceeds from a predetermined or selected end or flange of the reel 22 to secure invariably smooth unwinding and to prevent overlapping and catching in unreeling. The 110 interior of the hub 23 of said reel is preferably threaded on a rod 24 which extends

upwardly and may be secured to arm 25 pivoted at 26. On said arm is contact member 27 adapted to be brought into engagement with the contacts 28 and 29, for the purpose of placing the signalling means into operation. A spring 30 may be provided to insure a positive action, if desired. It will readily be seen that the unwinding of the reel as the buoy rises to the surface will 10 cause the switch to be closed.

Within the float 40 the sending apparatus proper is preferably located, which may comprise an inductive vibratory spark gap 80, and motor driven signal sending apparatus 81, all the apparatus being arranged to derive its energy from the batteries 35 in member 60.

Preferably in connection with the buoy I provide means to retard its ascent when released from the anchor cable. For this purpose a drag member 33 may be provided which is arranged somewhat in the form of an inverted parachute or an umbrella. Said member is shown as mounted near the top of float 40 on mast 41 but within the confines of the wires 42 forming the aerial. The parachute as shown may be made of some flexible material 36, which is held normally closed by raised ribs 37 made in the form of 25 springs coiled at the base at 37'. Said coil 30 may act as a stop to limit the opening of the parachute. In addition to or instead of said stop, light chains 39 may be provided for this purpose.

35 The antennae are shown as secured to an insulator 83 near the top of the mast, which insulates the same from the mast and from each other. A strain insulator 84 is provided for each wire. Preferably the mast is 40 made adjustable in height as by threading one portion 85 into another portion 86, so that the wires may be readily tightened. All projecting parts, such as the insulators 84 are covered or made conical in shape as 45 shown at 86' to avoid catching in the net as the buoy rises. All exposed portions such as the top of the mast and the member 60 are rounded for the purpose, also.

As stated above, in addition to securing 50 the nets to the anchor cable, the nets are preferably connected to each other. The preferred form of this connection is shown in Fig. 9, in which the top cable 49 of net 1 is shown as secured to a member 45 having a 55 hole 46 adjacent to its end, while cable 50 of net 2 is provided with a forked member 47. A shear pin 48 is driven therethrough and through the hole in member 45.

In order to prevent said pin from shear- 60 ing while the nets are being laid or launched, I may provide a ring or loop 68 adapted to be caught over the end cables 49 and 50 of nets 1 and 2 respectively, in the manner indicated in Fig. 8. A pin 51 may then be 65 driven or forced through a loop in one of the

cables as shown. I prefer to construct the said pin of some difficultly soluble substance, such as rock salt, cast in proper form so that after the net has been in the water for some time the pins will be dissolved and the nets 70 held only by the shear pins. The rock salt 51 may be covered with paraffin paper in order to protect the salt from moisture before the net is thrown overboard. The paper may be punctured as the net is being 75 launched.

A modified construction of the signalling switch is shown in Fig. 6. According to this modification the rotating of the reel does not draw the switch 27' down into engagement with the contacts 28 and 29 directly as in the preferred form, as the reel allows the spring 30 to force the switch down. According to this construction, the threaded rod 24' merely rests against the undersurface 85 of member 25' but is not positively secured thereto. The action of the switch may also be assisted or supplemented by making use of the variation in water pressure at the depth at which the buoy is anchored and at 90 the surface. For this purpose the stem or rod 24' is enclosed at its upper end by a housing 70 having expandable walls and in communication with the water through an opening 71. As the water pressure de- 95 creases on the rising of the buoy spring 30 will gradually force switch 27' down. By employing this additional means, the switch is prevented from operating by the unwinding of reel 22 only, but requires that the buoy 100 also be raised to the surface.

The operation of my invention is as follows: When a submarine boat strikes net 1 for instance, the net will be torn from the adjacent nets by the parting of the shear pins 48 and at the same time torn from the anchor cable at the shear pins 6. The buoy 10 will not be released immediately, however, but reel 8 will begin to pay out as the boat carries the net further away. When the end of 110 rope 9 is reached, it will be jerked off the snap hook 13, unlocking the said hook so that anchor cable 4, weight 11 and the other rope 9' are all released. The buoy will then start to rise, thereby unwinding reel 22, and 115 opening the retarding device or parachute 33. As the surface is approached, the operating switch 27 is thrown as explained thereby placing the wireless signally means in operation.

In accordance with the provisions of the patent statutes, I have herein described, the principle of operation of my invention, together with the apparatus, which I now consider to represent the best embodiment 125 thereof, but I desire to have it understood that the apparatus shown is only illustrative and that the invention can be carried out by other means. Also, while it is designed to use the various features and elements in the 130

combination and relations described, some of these may be altered and others omitted without interfering with the more general results outlined, and the invention extends to such use.

Having described my invention, what I claim and desire to secure by Letters Patent is:

1. An apparatus for indicating the presence of underwater craft including a signalling buoy, adapted to be anchored under water, a weight secured thereto, a snare adapted to be engaged by said craft, and means brought into operation by said snare 15 for releasing said weight from said buoy.

2. The combination with a cable adapted to be submerged in the sea, a net detachably secured thereto, a somewhat buoyant signalling buoy held thereby below the surface of the water and means brought into operation 20 by detachment of the net for increasing the buoyancy of said buoy and releasing it from said cable.

3. In an apparatus for detecting vessels, the combination with a signal buoy, of releasable means for anchoring it under water, means for releasing the same and a retarding device connected to said buoy to lessen the speed of ascent to the surface.

30 4. A signal buoy comprising a float, means for holding the same a predetermined distance below the surface of the water, releasing means therefor, and a drag member connected thereto to retard the rate of ascent.

35 5. The combination with a cable adapted to be submerged in the sea, of a signal buoy, releasable means for connecting said buoy and cable to hold the same under water, and an auxiliary connection for holding the buoy 40 when on the surface in the vicinity of the cable.

6. The combination with a cable adapted to be submerged in the sea, of a signal buoy, releasable means for connecting said buoy and cable to hold the same under water, a reel mounted in said buoy adapted to hold 45 a second connecting means, means for releasing said releasable means, a signalling device on said buoy, and means brought into 50 action by the unwinding of said reel for controlling said device.

7. The combination with a cable adapted to be submerged in the sea, of a signal buoy containing radio-transmission apparatus, releasable means for connecting said buoy and cable to hold the same under water, a reel mounted in said buoy adapted to hold a second connecting means, means for releasing said releasable means, a switch for energizing said apparatus, and means brought 60 into operation by the unwinding of said reel for operating said switch.

8. The combination with an anchoring means, of a signal buoy and a net detachably secured thereto, a hook in the connections 65

between said buoy and said means, and means connecting said net and said hook adapted to release it on the carrying away of said net.

9. The combination with a cable adapted 70 to be submerged in the sea, buoyant means on said cable for supporting part of the weight thereof, a net detachably secured thereto, a buoyant signalling buoy held thereby below the surface of the water, a weight attached to said buoy adapted to overcome a large part of its buoyant tendency and means brought into operation by the carrying away of the net for releasing said buoy from said cable and for casting 80 off said weight.

10. A radio-signalling buoy comprising a float, a mast attached thereto, antennæ stretched between said mast and float, means for holding the same a predetermined distance below the surface of the water, releasing means therefor, and a drag member connected thereto to retard the rate of ascent, said drag member being located with- 85 in the confines of said antennæ.

90 11. Apparatus for detecting and indicating the presence of a submarine boat comprising the combination of a net adapted to be submerged in the sea, a buoyant automatic signalling device, a pivoted hook on the signalling device, an anchor for holding the signalling device submerged connected to the hook, a pivoted latch coacting with the hook to form a closed connection between the anchor and the signalling device, a ring through which the connection extends, and a cable extending from the net to the ring whereby when the net is carried away by a submarine boat the latch is disengaged from the hook to release the signalling 95 device from its anchor and the ring is then disengaged from the connection to disconnect the net from the signalling device; substantially as described.

100 12. The combination with a cable adapted to be submerged in the sea, of a signal buoy, releasable means for connecting said buoy and cable to hold the same under water, means for releasing said releasable means, a reel mounted in said buoy adapted to hold a second connecting means, a signalling device on said buoy, hydrostatically operated means for causing actuation of said device, means for preventing said hydrostatically operated means from causing actuation of 115 said device, and means brought into action by the unwinding of said reel for rendering said preventing means inoperative.

13. The combination with a cable adapted to be submerged in the sea, of a net detachably secured thereto, a signal buoy releasably connected to said cable and held thereby below the surface of the water, means responsive to the carrying away of said net for releasing said buoy, and retarding means 125 180

connected to said buoy to lessen the speed of ascent to the surface.

14. The combination of a cable adapted to be submerged in the sea, of a net detachably secured thereto, a signal buoy normally held thereby below the surface of the water, means responsive to the carrying away of said net for releasing said buoy, a signalling device on said buoy, a reel mounted on said buoy and connected to said cable, and means brought into action by unwinding of said reel for controlling said device.

15. The combination with a cable adapted to be submerged in the sea, of a somewhat buoyant signalling buoy held thereby below the surface of the water, a reel in said buoy connected to said cable, means for increasing the buoyancy of said buoy and releasing the same from said cable, a signalling device on said buoy, and means brought into action by the unwinding of said reel for controlling said device.

16. A radio-signalling buoy comprising a float, a mast attached thereto, antennæ stretched between said mast and float, means 25 for holding the same a predetermined distance below the surface of the water, a net connected to said float for releasing the same, and a drag member connected thereto to retard the rate of ascent, said drag member 30 being located within the confines of said antennæ.

17. The combination with a cable adapted to be submerged in the sea, of a signal buoy, releasable means for connecting said buoy and cable to hold the same under water, a net connected to said buoy for releasing the same, and an auxiliary connection for holding the buoy when on the surface in the vicinity of the cable.

In testimony whereof I have affixed my signature.

ELMER A. SPERRY.
